UNITED STATES PATENT OFFICE

159,405

EDUCATIONAL GAME BOARD

Frederick R. Bossart, Detroit, Mich.

Application January 25, 1949, Serial No. 485

Term of patent 7 years

(Cl. D25—1)

To all whom it may concern:

Be it known that I, Frederick R. Bossart, a citizen of the United States, residing at Detroit, in the county of Wayne and State of Michigan, have invented a new, original, and ornamental Design for an Educational Game Board, of which the following is a specification, reference being had to the accompanying drawing, forming a part thereof, in which:

Fig. 1 is a top plan view of the educational game board, showing my new design; and

Fig. 2 is an edge view thereof.

The dominant features of my new design are shown in solid lines in the drawing.

I claim:

The ornamental design for an educational game board, substantially as shown and described.

FREDERICK R. BOSSART.
